UNITED STATES PATENT OFFICE.

SAMUEL G. GOSS, OF CHICAGO, ILLINOIS, AND RALPH C. SEYMOUR, OF LARCHMONT, NEW YORK, ASSIGNEES TO GOSS PRINTING PRESS COMPANY, A CORPORATION OF ILLINOIS.

CUTTING AND FOLDING MACHINE.

1,173,950.

Specification of Letters Patent. Patented Feb. 29, 1916.

Application filed June 10, 1914. Serial No. 844,153.

To all whom it may concern:

Be it known that we, SAMUEL G. GOSS, of Chicago, Illinois, and RALPH C. SEYMOUR, of Larchmont, New York, citizens of the 5 United States, have made Improvements in Cutting and Folding Machines, of which the following is a specification.

The invention relates to machines auxiliary to printing presses and like machines, 10 and more particularly to such machines wherein a running web is received and cut and folded and delivered or delivered unfolded.

The various objects of the invention will 15 be in part obvious and in part will be set forth hereinafter.

The invention consists in the novel parts, combinations, constructions, and improvements herein shown and described.

20 The accompanying drawings, referred to herein and forming a part hereof, illustrate one embodiment of the invention, and together with the description serve to explain the principles thereof.

25 Of the drawings:—Figure 1 is an elevation of a machine constituting an embodiment of the invention; Fig. 2 is an elevation of a somewhat different form of machine; Fig. 3 is a view similar to Fig. 2 but showing the parts in a different position, and the machine delivering unfolded sheets; Fig. 4 is a view on an enlarged scale of the central part of Fig. 3, showing the mechanism in a different position and with 30 certain parts omitted; and Fig. 5 is a fragmentary elevation on an enlarged scale showing a different form of web adjusting or compensating device.

35 Referring by way of example to the embodiment shown in Fig. 1 of the drawings, a suitable source of web supply is provided, such as a rotary perfecting printing press from which the web α is run in to the folding and cutting machine in a well known manner. In the drawings the web α is shown running in at the upper left part of Fig. 1, being fed forward between feeding rolls 1 and 2 mounted upon the machine frame 3.

40 Means are provided by the invention for making a complete cut or severance of the web, such as is required in the clean cut edges for magazines and other high class work. For this purpose the cutters are placed at a very slight angle that is,

obliquely, to the axis of their carriers, thereby giving a clean, shearing cut to the running web. In order that the shearing cut may be made in the running web by the transversely set blades and at the same time 60 that the cut may be made straight across, that is, perpendicular to the side edges of the web, means are provided for taking up the web slightly at one side and just sufficiently to compensate for the diagonal gain 65 of the cut across the web as it runs. Said compensating take-up is greatest at one edge of the web and gradually diminishes to nothing at the opposite side edge of the web. In accordance with certain features of the 70 invention such compensating device may be mounted upon some of the cutting or folding members, thereby dispensing with additional shafts and parts in the machine. Referring to the particular embodiment in Fig. 75 1, the web α is fed forward to a cylinder 4 having its shaft 5 journaled in the machine frame. Said cylinder 4 as embodied is provided with two cutting blades 6 and 7 mounted in the periphery of the cylinder 80 and having the oblique slant or set relatively to the axis 5 of the cylinder which has already been referred to. Coöperating with the cylinder 5 is a cylinder 8, having its shaft 11 journaled in the machine frame. 85 Said cylinder 8 is provided with cutting knives 9 and 10, said knives coöperating respectively with the knives 6 and 7 on cylinder 4 to cut the web as it is run through the machine, and as will be clear 90 from Fig. 1 of the drawings. In accordance with certain features of the invention, the cylinders 4 and 8 likewise act as folding cylinders, and in the embodied form shown in Fig. 1, the compensating 95 device for producing a perpendicular cut in the web is carried in part upon the cylinder 4. In the embodied form of such compensating device, upon the cylinder 4 there is formed, longitudinally along the cylinder, 100 a depression 15, deepest at one end, and becoming gradually shallower and narrower and diminishing to nothing at the other end, as will be clear from Fig. 6. The size of 105 said depression 15 is such as to just take up sufficient of the web to compensate for the oblique or shearing cut of the running web. A corresponding projection 16 fits into the depression 15 to force the web thereinto, and thus effect the necessary take-up. The pro- 110

jections 16 and corresponding depressions 15 are two in number, coöperating in pairs as will be well understood, one pair being shown in Fig. 1 taking up or compensating 5 the web. The projections 16 are carried by blocks 17 mounted upon disks or supports 18 fixed to a shaft 19 journaled in the frame of the machine.

The folding devices as embodied comprise 10 movable folding blades upon the cylinder 4, and coöperating folding jaws upon the cylinder 8. Folding blades 20 are carried by the cylinder 4 and are radially reciprocable out and back to effect the folding, in co- 15 operation with the folding jaws upon the cylinder 8. Each blade 20 is reciprocated by suitable connections and as embodied pin and slot connections 21 at each end of the blade. The slots 22 are formed in arms 23 fixed to a shaft 24 mounted in the cylinder 4, the arms 23 being acted upon by springs 25. Fixed to each shaft 24 is an actuating arm 26, provided with a cam roller 27, co- 20 operating with a cam 28 carried upon the machine frame. The folding jaws 30 into which the blades 20 fold, respectively, are likewise two in number and are carried upon the cylinder 8. Said folding jaws 30 are provided, respectively, with actuating shafts 25 31. The shafts 31 are provided with actuating arms 32 having cam rolls 33, and are acted upon by spring 34. A controlling cam 35 is carried upon the machine frame for 30 opening and closing the folding jaws to receive the folds from the folding blades, and also to deliver the folded product. The folding blades 20 are shown conveniently mounted in the depressions 15, the folding blades retracting or drawing in sufficiently far so as 35 not to interfere with the operation of the depressions 15 and projections 16.

Suitable delivery devices are provided, and in the embodied form thereof, a delivery cylinder 40 has its shaft 41 rotatably mounted in the machine frame. The cylinder 40 is provided with sets of grippers 42 and 43, which are provided with opening and closing means (not shown) to cause them to take the folded sheets from the folding jaws and 45 to release or deliver them at the proper point. The cylinder 40 is shown delivering to an intermittent pocket delivery or belt conveyer 45 mounted upon rollers 46 and driven by suitable means (not shown). A stripper 47 insures the delivering of the sheet to the carrier 45.

The manner of operation of the mechanism just described is substantially as follows:—The web α is run in from the printing press or other source between the feeding rollers 1 and 2, and about the cylinder 4, and then about the lower part of the cylinder 8, the lead end of the web being folded into the bite of the foldings jaws 30. As the cutters 60 7 and 9, or 6 and 10, come to the cutting po-

sition, or rather immediately prior thereto, the compensating depression 15 and the corresponding projection 16 draw one side of the web back just sufficiently to compensate for the oblique set of the cutters, and the shearing cut of the running web is thus made actually straight across the web or perpendicular to its side edges. The thus severed and folded sheet is delivered from the folding jaws 30 to one of the sets of grippers 42 75 upon the cylinder 40 and is then deposited upon the carrier 45. The new lead of the web, at the cut just made, runs down between cylinders 4 and 8, and the succeeding folding blade 20 and folding jaw 30 fold the center 80 of the next sheet into the folding jaw 30, and the next set of cutting blades sever the sheet as already described.

In the form of device shown in Figs. 2 and 3, the web is not only cut into 85 sheets but the sheets are likewise collected if desired. Referring particularly to the said figures, the web α is run in between feed rolls 48 and 49. A pair of traveling carriers are provided for the compensating take-up device for the web, and in Figs. 2 and 3 said compensating take-up device is shown of rotary form, and in Fig. 5 said device is shown in reciprocatory form. In Figs. 2 and 3 a cylinder 50 is provided with a compensating depression 51 arranged longitudinally thereof, or parallel to its axis, like the compensating depressions 15 heretofore described. A coöperating cylinder 53 mounted upon a suitable shaft 54 is 90 provided with a compensating projection 55, extending longitudinally thereof or parallel to its axis. The projection 55 is like the projections 16 already described, and coöperates with the compensating depression 51 in a 95 manner which will be understood upon the preceding description.

A cylinder 60 is carried upon a shaft 61 journaled in the machine frame. The cylinder 60 carries cutting blades 62 and 63, 110 which cutting blades are mounted at a slight angle or obliquely with respect to the axis of the cylinder 60. A cylinder 64 coöperates with the cylinder 61, and has cutting blades 65 and 66, coöperating respectively 115 with the cutting blades 62 and 63 on the cylinder 60. Suitable guides 67 may be provided to support and direct the web to the cylinders 60 and 64. The cylinder 64 is provided with means for retaining the 120 lead of the web, and so far as concerns many features of the invention said means may be of any desired form. As shown herein such means comprises impaling pins 68 and 69, mounted and operating in a well known 125 manner.

Means are provided by the invention for delivering the sheets unfolded, or for delivering the sheets singly folded, or for delivering the sheets collected and folded, 130

as may be desired. In the embodied form of such means, the folding devices comprise reciprocating folding blades 80 mounted in the cylinder 64. Said folding blades have 5 a pin and slot connection with the slots 81 in lever arms 82 at each end of the folding blades 80. The arms 82 are fixed, respectively, to rock shafts 83 carried by the cylinder 64. Springs 84 are connected to the 10 arms 82. Fixed to the shafts 83 are actuating arms 85, provided with cam rolls 86. Said cam rolls coöperate, respectively, with suitable cams 87 upon the machine frame, to project the folding blades 80 at the proper 15 time to fold the sheets into the corresponding folding jaws.

Coöoperating with the cylinder 64 to fold the sheets, is a cylinder 90 carried by shaft 91 journaled in the machine frame. The 20 cylinder 90 is provided with sets of folding jaws 92 of any suitable form. Folding jaws 92 are carried by rock shafts 93, said shafts 93 being mounted in the cylinder 90. Fixed to the respective rock shafts 93 is an actuating arm 94, carrying a cam roller 95, and acted upon by a spring 96. A cam 97 fixed upon the machine frame coöperates with the cam roller 95 to open and close the folding jaws to take the fold, and to deliver the 30 sheet.

The form of delivery devices shown comprises an intermittent carrier or conveyer belt 98 carried upon rollers 99 and driven in a suitable manner (not shown).

35 The form of flat delivery embodied in said Figs. 2 and 3 comprises tapes 110 and 111 running over rollers 112 and 113, and constituting a sheet pathway conducting away the sheets from the cylinders 60 and 40 64. Means are provided for directing the lead edge of the successive sheets between the tapes 110 and 111, to be conveyed away thereby. As embodied, a series of fingers 114 are carried in recesses in the cylinder 45 64. Said fingers 114 are mounted on a rock shaft 115, said shaft being mounted in the cylinder 64. Fixed to the rock shaft 115 is an actuating arm 116 provided with a cam roller 117. The cam roller 117 coöperates with a cam 118 on the machine frame.

50 The manner of operation of the mechanism just shown and described is substantially as follows:—The web *x* runs in between the feed rollers 48 and 49. When it is desired to cut the sheets and deliver them flat, the cam 118 is moved into operative relation with the cam roller 117, and the guiding and supporting fingers 114 raised as shown in full lines, and then pass through 55 the positions shown in dotted lines in Fig. 4, thus lifting the lead end of the web from cylinder 64 and feeding it into the tape pathway 110 and 111. The cutters 63 and 66 or the cutters 62 and 65 sever the sheet, 60 which is then conveyed away. When it is

desired to cut and fold, the grippers or impaling pins 68 carry the lead end of the web about the cylinder 64, and the folding blades 80 fold the center of the sheet into the folding jaws 92. The sheet is then released by the grippers or impaling pins 68 to the cylinder 90 and by said cylinder is delivered to the conveyer 98. When it is desired to collect, the folding blades and 70 folding jaws 80 and 92 respectively, and the grippers or impaling pins 68 are arranged to operate intermittently and periodically so as to take upon the cylinder 64 two or more sheets in super-imposition and then fold them off together in the manner already described for a single sheet.

75 From all the foregoing it will be understood that a machine has been provided embodying the objects and advantages herein set forth, together with other objects and advantages. It will be understood also that changes may be made from the mechanisms shown and described within the scope of the accompanying claims, without departing from the principles of the invention and 80 without sacrificing its chief advantages.

85 What I claim as my invention and desire to secure by Letters Patent is:—

1. A folding and cutting machine including in combination a traveling member carrying an obliquely positioned cutter, a compensating device, and carrying also a member of a device for folding the cut sheet, and traveling means carrying a coöperating compensating device and a coöperating folding device.

95 2. A folding and cutting machine including in combination a rotary member carrying an obliquely positioned cutter, a compensating device, and carrying also a member of a device for folding the cut sheet, and traveling means carrying a coöperating compensating device and a coöperating folding device.

105 3. A folding and cutting machine including in combination a traveling member carrying an obliquely positioned cutter, a compensating device, and carrying also a member of a device for folding the cut sheet, and rotary means carrying a coöperating compensating device and a coöperating folding device.

110 4. A folding and cutting machine including in combination a rotary member carrying an obliquely positioned cutter, a compensating device, and carrying also a member of a device for folding the cut sheet, and rotary means carrying a coöperating compensating device and a coöperating folding device.

115 120 5. A folding and cutting machine including in combination a traveling member carrying an obliquely positioned cutter, a compensating device, and carrying also a member of a device for folding the cut sheet,

- sating device for producing a perpendicular cut from said oblique cutter, a coöperating oblique cutter and a coöperating folding device.
- 5 21. A folding and cutting machine including in combination a web supply, a member carrying an obliquely arranged cutter and carrying a member of a folding device for folding the cut sheets, a rotary compensating device for producing a perpendicular cut from said oblique cutter, a coöperating oblique cutter and a coöperating folding device.
- 10 22. A folding and cutting machine including in combination a web supply, a traveling member carrying an obliquely arranged cutter and carrying a member of a folding device for folding the cut sheets, a traveling compensating device for producing a perpendicular cut from said oblique cutter, a coöperating oblique cutter and a coöperating folding device.
- 15 23. A folding and cutting machine including in combination a web supply, a rotary member carrying an obliquely arranged cutter and carrying a member of a folding device for folding the cut sheets, a rotary compensating device for producing a perpendicular cut from said oblique cutter, a coöperating oblique cutter and a coöperating folding device.
- 20 24. A folding and cutting machine including in combination a web supply, a member carrying an obliquely arranged cutter and carrying a member of a folding device for folding the cut sheets, a compensating device for producing a perpendicular cut from said oblique cutter, a coöperating oblique cutter and a traveling coöperating folding device.
- 25 25. A folding and cutting machine including in combination a web supply, a member carrying an obliquely arranged cutter and carrying a member of a folding device for folding the cut sheets, a compensating device for producing a perpendicular cut from said oblique cutter, a coöperating oblique cutter and a rotary coöperating folding device.
- 30 26. A folding and cutting machine including in combination a web supply, a traveling member carrying an obliquely arranged cutter and carrying a member of a folding device for folding the cut sheets, a traveling compensating device for producing a perpendicular cut from said oblique cutter, a coöperating oblique cutter and a traveling coöperating folding device.
- 35 27. A folding and cutting machine including in combination a web supply, a rotary member carrying an obliquely arranged cutter and carrying a member of a folding device for folding the cut sheets, a rotary compensating device for producing a perpendicular cut from said oblique cutter, a coöperating oblique cutter and a traveling coöperating folding device.
- 40 28. A folding and cutting machine including in combination a web supply, a member carrying an obliquely arranged cutter and carrying a member of a folding device for folding the cut sheets, a traveling compensating device for producing a perpendicular cut from said oblique cutter, a coöperating oblique cutter and a traveling coöperating folding device.
- 45 29. A folding and cutting machine including in combination a web supply, a member carrying an obliquely arranged cutter and carrying a member of a folding device for folding the cut sheets, a rotary compensating device for producing a perpendicular cut from said oblique cutter, a coöperating oblique cutter and a rotary coöperating folding device.
- 50 30. A folding and cutting machine including in combination a web supply, a cylinder having an obliquely arranged cutter and having a folding device, a cylinder carrying a coöperating oblique cutter, coöperating folding means, and compensating means for causing said cutters to make a perpendicular cut in the web.
- 55 31. A folding and cutting machine including in combination a web supply, a cylinder having an obliquely set cutter, and a folding device, and having also a compensating device for causing said oblique cutter to make a perpendicular cut, a coöperating cylinder having coöperating cutting and folding means, and means coöperating with said compensating device for making the perpendicular cut.
- 60 32. A folding and cutting machine including in combination a web supply, a cylinder having an obliquely set cutter, and a folding device, and having also a compensating device for causing said oblique cutter to make a perpendicular cut, a coöperating cylinder having coöperating cutting and folding means, and a cylinder carrying means coöperating with said compensating device for making the perpendicular cut.
- 65 33. A folding and cutting machine including in combination a member carrying an oblique cutter and a compensating device, and carrying also a folding device, a member carrying a coöperating oblique cutter and carrying also a coöperating folding device, and means coöperating with said compensating device.
- 70 34. A folding and cutting machine including in combination a traveling member carrying an oblique cutter and a compensating device, and carrying also a folding device, a member carrying a coöperating oblique cutter and carrying also a coöperating folding device, and means coöperating with said compensating device.
- 75 35. A folding and cutting machine including in combination a web supply, a cylinder having an obliquely set cutter, and a folding device, and having also a compensating device for causing said oblique cutter to make a perpendicular cut, a coöperating cylinder having coöperating cutting and folding means, and a cylinder carrying means coöperating with said compensating device.

cluding in combination a member carrying an oblique cutter and a compensating device, and carrying also a folding device, a traveling member carrying a coöperating oblique cutter and carrying also a coöperating folding device, and means coöoperating with said compensating device.

36. A folding and cutting machine including in combination a traveling member carrying an oblique cutter and a compensating device, and carrying also a folding device, a traveling member carrying a coöperating oblique cutter and carrying also a

coöperating folding device, and means coöperating with said compensating device. ¹⁵
